United States Patent Office

Des. 175,154
Patented July 19, 1955

175,154

LAMP BASE OR SIMILAR ARTICLE

Eve Cohen, West Orange, N. J.

Application November 2, 1954, Serial No. 32,917

Term of patent 7 years

(Cl. D48—20)

The figure is a front elevational view of a lamp base showing my new design. The design is substantially circular throughout its height. The dominant features of my new design are shown in solid lines.

I claim:

The ornamental design for a lamp base or similar article, as shown and described.
